Primary Examiner — Marianne Pandozzi*Assistant Examiner* — Jae Liang(74) *Attorney, Agent, or Firm* — Schiff Hardin LLP(57) **CLAIM**

The ornamental design for a cup, as shown and described.

DESCRIPTION

FIG. 1 is a top, front, and right side perspective view of a cup showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a bottom, front and left side perspective view thereof; and,

FIG. 9 is a top, front, and right side perspective view thereof in use with an unclaimed lid.

The broken lines in the drawing depict environmental subject matter only and form no part of the claimed design.
